WIRE CLOTH TIGHTENER

Loren G. Symons, Hollywood, Calif., assignor to
 Symons Brothers Development Company,
 Hollywood, Calif., a corporation of Delaware

Application June 11, 1931, Serial No. 543,572

3 Claims. (Cl. 209—403)

My invention relates to an improvement in screens and has for one purpose the provision of an improved screen deck. One particular purpose is the provision of improved tightening means for tightening or taking up the slack in a wire cloth screen deck. Another object is the provision of a readily removable wire cloth member from a screening deck or frame. Another object is the provision of means for maintaining a screen deck under tension. Other objects will appear from time to time in the course of the specification and claims.

I illustrate my invention more or less diagrammatically in the accompanying drawings, where-

15 in—
 Figure 1 is a plan view;

Figure 2 is a side elevation partly in section;

Figure 3 is a detail;

20 Figure 4 is a partial end elevation partly in section;

Figure 5 is a section on the line 5—5 of Figure 4; and

Figure 6 is a detail.

Like parts are indicated by like symbols 25 throughout the specification and drawings.

Since my invention relates to a screen deck which may be mounted in a variety of manners I have not illustrated the details of any particular screen mounting or support. I therefore illustrate only the deck proper which may include for example the side frame members A, A¹, which may be of angle iron, channel iron or the like but are here shown as formed of a web A² with flanges A³ A⁴ extending in opposite directions 30 from the opposite edges thereof. The members A, A¹ may be connected by any suitable cross members. I illustrate for example the angles A⁵ A⁶ adjacent the center of the screen and the pipes or cylindrical members A⁷ A⁸, arranged in 35 groups, the members A⁷ being positioned between the angle A⁵ and one end of the screen and the members A⁸ being positioned between the angle A⁶ and the opposite end of the screen.

Secured to each of the members A⁵ A⁶ are 40 screen cloths B B¹ respectively. Their inner edges may be secured to the angles as by the clamping strips B², the bolts B³ and the nuts B⁴. It will be understood that this is illustrated merely as an example of attaching means where- 45 by the inner edge of the members B or B¹ may be readily and removably secured to the angles A⁵ or A⁶. The opposite end of each of the members B or B¹ extends about a reel or pipe or cylinder B⁵ at the end of the screen. The members B⁵ 50 fit into notches B⁶ in the screen ends and the

ends of the mesh sections B or B¹ pass thereabout as at B⁷, being secured for example by bolts B⁸, nuts B⁹ and washer B¹⁰.

Secured to the side screen frame members A² adjacent their ends and also formed or notched for the penetration of the rolls B⁵ are the fixed plates C which may for example be welded to the web A² of the side frame members A or A¹. Rotatable in relation to each end of each roll B⁵ is a disc C¹. This disc C¹ is centered by the roll B⁶, upon which it is threaded, but may be held against rotation in relation to the plate C for example by a bolt C² which passes through any one of the apertures C³ about the periphery of the plate C¹. Some of the apertures C³ communicate by notches C⁴ with the periphery of the disc C¹. In tightening up the device the operator may employ the tool generally indicated as E in Figure 6 which includes a handle portion E¹, an eye E² adapted to surround the plate C¹ 10 and an abutment E³ adapted to penetrate the notches C⁴. The operator may thereby rotate the plate C¹ to draw out upon the screen member B or B¹ until the desired tension is obtained. The bolt C² is then inserted through the side 15 frame web A², the plate C and the disc C¹.

If desired yielding means may be employed to maintain the roller B⁵ positioned to wind in on the screen cloth. I may employ for example the coil spring D one end of which is secured to 20 a pin or abutment or bolt D¹ on the member B⁵, the other engaging an abutment D² on the disc C¹. The spring D tends at all times to reel in on the roller B⁵ and thus to maintain the screening member B or B¹ under constant tension. 25 The tool E may be employed to rotate the disc C¹ to relieve the tension on the spring, in order to permit release of the screen from the roll B⁶ and removal of the screen B or B¹ from the 30 deck.

It will be realized that whereas I have described and shown a practical and operative device, nevertheless many changes might be made in size, shape, number and disposition of parts without departing from the spirit of my invention. I therefore wish my description and drawings to be taken as in a broad sense illustrative and diagrammatic rather than as limiting me to my specific showing.

The use and operation of my invention are as 45 follows:

I find it desirable to maintain a screen deck of wire mesh or the like under constant tension. My roller B⁵ with the spring D is an efficient means of obtaining this result. The spring D 50

tends at all times to roll the roller in and to put tension on the cloth section B or B¹. I find it desirable but not necessary to divide the screen surface into a plurality of units. A convenient arrangement is to employ two units, secured to the screen deck at the middle of the deck, and each secured to a separate spring actuated roller B⁵ at the end of the deck. In case there is unevenness at different parts of the screen, this arrangement enables one section to be removed at a time without disturbing the remaining section.

It will be observed that the supports A⁷ and A⁸ are so arranged as to more or less arch the screen and give it transverse support throughout the screen deck. The screen is also held down against the members A⁷ A⁸, adding to the rigidity of the screen and limiting its flexure during use. Thus substantially the sole vibration imparted to the screen cloth is the vibration actually imparted to the deck or frame itself, and secondary vibration of the screen cloth is prevented.

I claim:

1. In a screen, a screen frame, longitudinal members therefor, transverse members connecting the longitudinal members intermediate their ends, a plurality of screen members, each removably secured to a transverse member intermediate the ends of the frame, a rotary member mounted upon each end of the screen frame, to which one of said screen members is secured, and means for rotating said rotary member and for thereby maintaining said screen member under tension, said means including helical springs generally concentric with the axis of rotation of said rotary member, one end of each such spring being secured in relation to the screen frame, the other being secured in relation to the rotary member.

2. In a screen, a screen frame, longitudinal members therefor, transverse members connecting the longitudinal members intermediate their ends, a plurality of screen members, each removably secured to a transverse member intermediate the ends of the frame, a rotary member mounted upon each end of the screen frame, to which one of said screen members is secured, and means for rotating said rotary member and for thereby maintaining said screen member under tension, said means including helical springs generally concentric with the axis of rotation of said rotary member, one end of each such spring being secured in relation to the screen frame, the other being secured in relation to the rotary member, and means for adjusting tension upon said screen members. 10 15

3. In a screen, a screen frame, longitudinal members therefor, transverse members connecting the longitudinal members intermediate their ends, a plurality of screen members, each removably secured to a transverse member intermediate the ends of the frame, a rotary member mounted upon each end of the screen frame, to which one of said screen members is secured, and means for rotating said rotary member and for thereby maintaining said screen member under tension, said means including helical springs generally concentric with the axis of rotation of said rotary member, one end of each such spring being secured in relation to the screen frame, the other being secured in relation to the rotary member, and means for adjusting tension upon said screen members, including a rotatably adjustable abutment for each such spring, said abutment being normally fixed in relation to the screen frame during use of the screen, and means for positioning it in relation to the screen frame at a plurality of adjustments. 20 25 30 35
